UNITED STATES PATENT OFFICE.

LEO J. WERNER, OF ARLINGTON, NEW JERSEY, ASSIGNOR TO SPLITDORF ELECTRICAL COMPANY, OF NEWARK, NEW JERSEY.

CIRCUIT-BREAKER.

1,304,837.

Specification of Letters Patent. Patented May 27, 1919.

Application filed November 16, 1918. Serial No. 262,778.

To all whom it may concern:

Be it known that I, LEO J. WERNER, a citizen of Russia, residing at Arlington, in the county of Hudson and State of New Jersey, 5 U. S. A., have invented certain new and useful improvements in Circuit-Breakers, of which the following is a specification.

This invention relates to circuit breakers used in connection with ignition generators, 10 preferably of the magneto type, in which a circuit breaker is used for controlling the time of producing the ignition impulses. By way of illustration, I have shown my circuit breaker as applied to a magneto of the 15 Dixie type, in which the generating coil is stationary, being carried on relatively fixed pole pieces which are carried on integral bearing members that are adjustable for timing purposes. For certain classes of 20 work, it is preferable to keep the field poles and generating coil stationary and when this is done, to get variation in the time of the spark, an adjustable circuit breaker must be used.

25 It is the object of my invention to provide a circuit breaker for this class of work which is simple in design and hence cheap to manufacture.

In the drawings, Figure 1 is an end view 30 of a magneto showing the breaker in position but with the cover removed.

Fig. 2 is a sectional view on the line 2—2 of Fig. 1.

Fig. 3 is a plan view of the breaker mechanism shown in Fig. 1.

Fig. 4 is a bottom view of the breaker mechanism shown in Fig. 1.

Referring now to the details, wherein like numbers refer to corresponding parts in the 40 various views, 1 is the end plate of the magneto carrying a distributor block 2. On the bottom part of the plate 1 is fastened a base plate 3 by screws, one of which is shown at 4. Plate 3 has a central opening 5 within 45 which is piloted a breaker base 6. A groove 13 in the top part of the base plate 3 is adapted to be filled with a suitable strip of felt which is engaged by the lower part of the distributor block 2 to prevent dust and 50 dirt from working up into the working space within the distributor block. To the breaker base 6, but insulated therefrom, is fastened a contact block 7 carrying an adjustable contact 8. Mounted on the block 6 but not 55 insulated from it, is a movable breaker arm

9 carrying a contact 10. The breaker arm 9 is held in operative position by a resilient member 11, the free end resting in the usual manner on the bearing 12. Fastened to the base plate 3 are studs 14 and 15, the outer 60 extremities of which carry a yoke 16. The yoke 16 has a central aperture adapted to receive a hollow bearing member 17. Within the hollow part of member 17 is a movable bushing 18, on the inner end of 65 which is attached the central part of a yoke 19, the outer extremities of which carry studs 20 and 21 that are fastened securely to the breaker base 6. A spacing member 22 is preferably used on the bushing 18 between 70 the yokes 16 and 19. The outer extremity of the bushing 18 is flattened off as at 23 and on these flat portions is mounted a lever arm 24, which is put in place after the cover 25 has been placed in position, a spacing washer 75 26 being used between the cover and the lever 24. The lever 24 is held in place by a nut 27 engaging a contact stud 28 which passes through an insulator 29 seated within the bushing 18 and an insulating bushing 30 80 85 that is cut out to receive the nut 27, the outer part of which is preferably covered with insulating material. A spring 31 fastened to the block 7 has its free end resting against the inner head of the contact stud 35 28, thereby forming an electrical circuit from the contact block 7 to the outer end of the stud 28 for a purpose which will be later referred to.

From the above described construction it 90 will be seen that the breaker base 6 is movable with the lever 24 and since the breaker members 7 and 9 are carried on the member 6, the time at which the cam on the rotating part of the magneto 1 hits the bumper 32 95 can be varied at will. For the sake of clearance the shaft of the magneto with the cam is omitted from the view, but it will be understood that the cam is in proper position and operated to engage the bumper 32. 100 A piece of felt 33 saturated with oil, for the purpose of lubricating the cam, is carried on the member 6.

Since the parts of the breaker are movable, as above described, some sort of flexible connection must be provided for the wire coming from the primary of the induction coil and rather than have the wire itself move, I have adopted a method of connection, as illustrated in Figs. 1 and 4, in which the pri- 110

mary winding is connected to a stud 34, the outer end of which carries a resilient member 35 that engages the surface of the block 7 thereby providing a permanent rubbing contact with the block 7. A contact of this character is not apt to be broken off or put out of commission, due to the continued operation of the breaker base carrying the breaker members.

10 While I have shown the application of my invention to one particular type of magneto, I do not wish to be limited in this respect as it may be applied to other types of ignition generators; while I have shown one 15 method of bringing out the insulated contact of the circuit breaker by way of stud 28 and associated parts, for the purpose of attaching the wire to run to a control switch, I do not wish to be limited to these exact 20 details.

Having thus described my invention, what I claim is:

1. In a circuit breaker mechanism the combination of a base plate having a hole 25 therein, a breaker base having a pilot to fit the hole in said base plate and carrying breaker parts consisting of stationary and movable members, a yoke fastened to but spaced apart from said base plate and carrying a bearing, a bushing movably fitted in said bearing and carrying a yoke having 30 studs attached to said breaker base and means associated with said bushing for moving it and the breaker base as described.

2. In a circuit breaker mechanism the combination of, a base plate having studs fastened thereto, a yoke carried by said studs, a second yoke movably carried by the first and having studs attached thereto, a 40 breaker base fastened to the last mentioned studs but guidingly supported by said base plate carrying breaker parts consisting of stationary and movable members and means for moving the movable yoke and breaker base for the purpose described.

3. In a circuit breaker mechanism the combination of, a base plate having studs fastened thereto, a yoke carried on the outer ends of said studs, a bearing in said yoke, 45 a movable bushing in said bearing, a yoke carried on one end of said bushing and hav-

ing supports fastened thereto, a breaker base fastened to said supports but also guidingly supported by the base plate and carrying stationary and movable breaker members, a 55 cover for the breaker members fitting around the base plate and said bearing and a control lever attached to one end of the said bushing outside the cover for moving the breaker base as described. 60

4. In a circuit breaker mechanism the combination of, a base plate having studs fastened thereto, a yoke carried on the outer ends of said studs, a bearing in said yoke, a movable bushing in said bearing carrying 65 an insulator and contact stud within the insulator, a yoke carried on one end of said bushing and having supports fastened thereto, a breaker base fastened to said supports but also guided in its movements by 70 the base plate, movable and relatively stationary contact members carried by the breaker base the stationary contact member being insulated therefrom, a rubbing contact member engaging the insulated contact member and a yielding member extending between the said stationary insulated contact member and the said contact stud carried by the said bushing for the purpose described and means fastened to the 75 other end of said bushing for moving it and the breaker base.

5. In a circuit breaker mechanism the combination of, a base plate carrying a yoke member spaced away but in front of it, a 80 breaker base carrying movable and stationary contact members rotatably supported by and between said yoke member and base plate and means for rotatably moving said breaker base for the purpose described. 85

6. In a circuit breaker mechanism the combination of, a base plate carrying a yoke member spaced away but in front of it, a breaker base carrying contact operating 90 means rotatably supported by and between said yoke member and base plate, a cover for said breaker base and parts mounted thereon and means outside the cover for rotatably moving said breaker base as described. 95

In witness whereof, I affix my signature.

LEO J. WERNER.
